UNITED STATES PATENT OFFICE.

GEORGE WASHINGTON HUNTER, OF LOGANSPORT, INDIANA.

DESIGN FOR A HEAD FOR DOOR OR WINDOW CASINGS.

46,676.

Specification for Design.

Patented Nov. 24, 1914.

Application filed June 22, 1914. Serial No. 846,689. Term of patent 7 years.

To all whom it may concern:

Be it known that I, GEORGE W. HUNTER, a citizen of the United States, residing at Logansport, in the county of Cass and State of Indiana, have invented a new, original, and ornamental Design for a Head for Door or Window Casings, of which the following is a specification, reference being had to the accompanying drawing, forming part thereof.

The figure is an elevation of a door or window casing, showing my new design.

I claim:

The ornamental design for a head for a door or window casing substantially as shown.

GEORGE WASHINGTON HUNTER.
